PACKAGING OF SELF-SEALING SHINGLES

Phillip S. Bettoli, Belle Mead, N. J., and Evereth L. Lyons, Riverdale, N. Y., assignors to The Ruberoid Co., New York, N. Y., a corporation of New Jersey

Application March 6, 1957, Serial No. 644,390

3 Claims. (Cl. 206—60)

This invention relates to a shingle package, and more particularly to the packaging of self-sealing shingles, especially asphalt strip shingles of the square-butt type that have adhesive material applied in broken or continuous lines, dots, or other figures, extending lengthwise of the shingles on the weather surface. The adhesive material is of such nature and so positioned that when the shingles are applied to a roof and subjected to solar heat the butt or exposed portion of the shingles will be sealed or cemented down by the self-acting effect of the adhesive.

Because of the adhesive material applied to the surface of the shingles, considerable difficulty has heretofore been experienced in packing the shingles for shipment from the factory without causing them to become somewhat deformed while they are contained in the package, and consequently interfering with proper and effective sealing when they are applied on the roof.

The thickness of the adhesive material on the weather surface of each shingle is slight, amounting usually only to about a few thousandths of an inch. However, as in packaging a plurality of shingles are bundled in each wrapper, the cumulative effect of the thickness of the adhesive material is considerable, being enough to cause the shingles to bend out of their normally flat condition. It is common practice in the industry to pack the shingles in bundles so that a given number of bundles will contain the number of shingles required to cover a "square," that is, to cover one hundred square feet of roof area.

It is an object of our invention to provide a packaging for transportation of self-sealing shingles that will protect the contents and avoid any objectionable bending or deformation of the shingles while in the package.

Other advantages of the invention will appear from the following description thereof, reference being had to the accompanying drawings, in which:

Fig. 1 is a perspective view of one form of the wrapper element of the package embodying the invention;

Fig. 2 is a perspective view of a panel or pallet for insertion in the package;

Fig. 3 is a perspective view of a modified form of the panel or pallet;

Fig. 4 is a plan view of a blank from which the wrapper element of the package may be formed, the blank in this instance having a continuous opening in the portion thereof that constitutes the bottom of the package;

Fig. 5 is a vertical view in section of the package and its contents, the latter being shown in phantom; and

Fig. 6 is a fragmentary perspective view of one form of self-sealing shingle to be bundled.

The fragmentary view of the shingle 10 illustrated in Fig. 6 is typical of one form of self-sealing shingle that is to be contained in the package. In this form, the shingle has a series of substantially rectangular forms of adhesive material 11 applied lengthwise on the upper or weather surface in a predetermined arrangement and at a prescribed distance above the inner or upper ends of the cut-outs or slots 12 that define the side edges of the so-called "square-tabs" of the shingle. In this instance, the

2

shingle has a stripe of parting material 13 on its lower or rear surface to prevent the shingles from sticking together when packed or stacked one upon another.

While the adhesive material is preferably in the form of separated rectangular figures, it may be applied in globules, in a continuous strip, or in other forms. In some instances the parting stripe may be eliminated and in lieu thereof the face of the adhesive may be covered with anti-stick paper or other substance that can be easily stripped or peeled off when the shingles are to be laid or applied on a roof.

In Fig. 6, for the sake of illustration, the thickness of both the adhesive 11 and the parting stripe 13 is greatly exaggerated in respect to that of the body of the shingle. Usually the thickness of the adhesive is only a few thousandths of an inch, about .020", and that of the parting stripe or material is negligible.

However, it is customary to pack the shingles in bundles so that a specified number of bundles will contain a sufficient quantity of shingles to cover a "square" of roof surface. Where the shingle bundles were packed in the conventional manner, it was found that, as the shingles are flexible, the cumulative effect of the thickness of the adhesive caused the shingles to sag and become deformed, especially if they were kept packed for any length of time before being used.

Our improved packaging supports the shingles at intervals on pallets and compensates for the increased thickness due to the adhesive material. This eliminates or minimizes deformation, and permits of removing the shingles from the packages and applying them to the roof in substantially their original flat condition.

The wrapper element, indicated generally by the numeral 14, of the package is formed from a flat blank of corrugated board or the like. The board is scored so that it may be bent to provide a bottom wall 15, parallel side walls 16, and a pair of top portions or flaps 17, the opposed edges 18 of which are spaced apart. In the form of wrapper of Fig. 1, the bottom has a series of aligned die-cut slots or openings 19 while in the form of Fig. 5, the bottom has a single continuous opening 20.

The package, as seen in Fig. 5, includes a plurality of pallets or panels 21 upon which stacks or catches of the shingles are supported face up. The pallets 21 are formed of flat rectangular sheets of corrugated board or the like, which are die-cut to provide a series of slots or openings 22 or a continuous opening 23, which openings correspond substantially in position, size, and arrangement to those of the openings 19 or 20 of the wrapper and are positioned with relation to the positioning of the adhesive 11 on the face of the shingles.

Each pallet 21 not only serves to support a given number of shingles so as to prevent them from bending but also, by reason of the slots or openings therein, compensates for the increased thickness of the supported shingles resulting from the application of adhesive on the face of the shingles.

The openings 19, 20 and 22, 23 of the wrapper and the pallets, respectively, are preferably of such width as to accommodate the adhesive material 11 and the parting stripe 13. The spacing between the opposed edges of the flaps 17 is preferably of the same order as the width of the openings in the bottom of the wrapper and in the pallets.

In packing the shingles, the wrapper element is bent to shape and a specified number of shingles are stacked face up on the bottom wall of the wrapper. Other shingles, usually of the same number as those supported on the bottom of the wrapper, are supported on each of the pallets that are inserted in and form a part of the complete package. The package is then bound in the usual manner with round tie-wires or metal straps 24.

We have found that double-faced corrugated board of the kind known in the trade as "A," "B," or "C" flute, varying in thickness from $\frac{1}{8}$ " to $\frac{3}{16}$ " may be used satisfactorily for making the wrapper and the pallets. However, we do not limit use to these particular materials as other suitably strong and inexpensive materials may be employed.

Pallets of the form of Fig. 2 are preferred to those of the form of Fig. 3, except where the adhesive is applied as a continuous strip, because the solid uncut portions between the openings in the pallet give it additional strength, and afford additional support to the shingles stacked thereon.

In packaging self sealing square-butt shingles having an overall measurement of 12" x 36", designed to be exposed five inches to the weather, they are usually packed in bundles, each containing about twenty-seven shingles, three such bundles being sufficient to cover a "square" of roof area. In that case, two pallets are included in each bundle or package, as indicated in Fig. 5, and the shingles in each bundle are divided into three stacks of nine shingles each. Where shingles of different dimensions and exposures are to be packed, fewer or more shingles may be contained in each stack, and the number of pallets used in each bundle, and the number of bundles required per "square," may be varied accordingly.

In storage and in shipping, a considerable number of packages of shingles are piled one upon another. Where the shingles are packed in ordinary cartons or wrappers, the weight of the pile effects a very considerable pressure on the shingles. In the case of self sealing shingles having raised adhesive areas, that pressure is concentrated largely on the high spots and tends to flatten the adhesive and/or to cause the shingles to stick together, particularly where they are subjected in storage or shipment to conditions of high heat.

The slotted wrapper and pallets of our improved package overcome these difficulties by relieving pressure on the adhesive areas (which constitute only a relatively small portion of the whole shingle area), and distributing the pressure substantially uniformly over the rest of the area.

It is to be understood that modifications in the package as herein described, and illustrated in the drawings, may be made within the scope of the invention as set forth.

What we claim is:

1. A package of self-sealing shingles comprising a wrapper having a bottom wall, a pair of substantially parallel side walls, a top flap along the upper edge of each side wall foldable inwardly upon the content of the wrapper, a stack of shingles supported in face-to-back relationship on the bottom of the wrapper, each shingle having a deposit of adhesive material on its weather surface located thereon in a predetermined position and arrangement, the shingles being stacked with the adhesive material of each in the same position, an additional stack or stacks of like shingles superposed on the first stack, each additional stack being supported on a pallet, the shingles of each additional stack being disposed in the same relationship to one another as those of the first

stack, each pallet being provided with one or more openings positioned with relation to the adhesive to accommodate and compensate for the localized cumulative added thickness of the stacks of shingles due to the deposit of adhesive material on each shingle.

2. A package of self-sealing shingles comprising a wrapper having a bottom wall, a pair of substantially parallel side walls, a top flap along the upper edge of each side wall foldable inwardly upon the content of the wrapper, a stack of shingles supported in face-to-back relationship on the bottom of the wrapper, each shingle having a deposit of adhesive material on its weather surface located thereon in a predetermined position and arrangement, the shingles being stacked with the adhesive material of each in the same position, an additional stack or stacks of like shingles superposed on the first stack, each additional stack being supported on a pallet, the shingles of each additional stack being disposed in the same relationship to one another as those of the first stack, each pallet being provided with one or more openings positioned with relation to the adhesive to accommodate and compensate for the localized cumulative added thickness of the stacks of shingles due to the deposit of adhesive material on each shingle, the bottom wall being provided with an opening or openings corresponding substantially in size, shape, and location to the openings in each pallet.

3. A package of self-sealing shingles comprising a wrapper having a bottom wall, a pair of substantially parallel side walls, a top flap along the upper edge of each side wall foldable inwardly upon the content of the wrapper, said flaps having opposed substantially parallel inner edges, a stack of shingles supported in face-to-back relationship on the bottom of the wrapper, each shingle having a deposit of adhesive material on its weather surface located thereon in a predetermined position and arrangement, the shingles being stacked with the adhesive material of each in the same position, an additional stack or stacks of like shingles superposed on the first stack, each additional stack being supported on a pallet, the shingles of each additional stack being disposed in the same relationship to one another as those of the first stack, each pallet being provided with one or more openings positioned with relation to the adhesive to accommodate and compensate for the localized cumulative added thickness of the stacks of shingles due to the deposit of adhesive material on each shingle, the bottom wall being provided with an opening or openings corresponding substantially in size, shape, and location to the openings in each pallet.
